DESIGN FOR AN ELECTRIC FIXTURE

William Lescaze, New York, N. Y., assignor to
Pass & Seymour, Inc., Syracuse, N. Y., a corporation of New York

Application May 22, 1936, Serial No. 62,783

Term of patent 7 years

To whom it may concern:

Be it known that I, William Lescaze, a citizen of the United States and resident of city, county, and State of New York, have invented a new, original, and ornamental Design for an Electric Fixture, of which the following is a specification, reference being had to the accompanying drawing, forming a part thereof, and in which:

Figure 1 is a perspective view of an electric fixture showing my new design; and

Figure 2 is a side elevation thereof.

I claim:

The ornamental design for an electric fixture substantially as shown.

WILLIAM LESCAZE.
